UNITED STATES PATENT OFFICE.

AURELIUS E. NEWMAN AND LE ROY JAMES, OF OSPUR, ILLINOIS.

FENCE-POST.

SPECIFICATION forming part of Letters Patent No. 543,398, dated July 23, 1895.

Application filed February 16, 1895. Serial No. 538,656. (No model.)

To all whom it may concern:

Be it known that we, AURELIUS E. NEWMAN and LE ROY JAMES, of Ospur, in the county of De Witt and State of Illinois, have 5 invented certain new and useful Improvements in Fence-Posts; and we do hereby declare that the following is a full, clear, and exact description of the invention, which will enable others skilled in the art to which it applies to make and use the same, reference being had to the accompanying drawings, and to the letters of reference marked thereon, which form part of this specification.

This invention relates to certain improvements in fence-posts.

The object of the invention is to provide an improved fence-post, exceedingly simple, strong, durable, and economical in construction, and so formed as to be easily planted and 20 capable of supporting wire or rails.

A further object of the invention is to provide certain improvements in the construction and arrangements of parts in fence-posts, whereby a highly-improved efficient post is 25 provided.

The invention consists in certain novel features of construction and in combination of parts more fully and particularly described hereinafter, and pointed out in the claims.

Referring to the accompanying drawings, Figure 1 is a rear perspective view of the post and its base. Fig. 2 is a front elevation. Fig. 3 is a longitudinal central section through the post and base, showing the peculiar wire-fastening devices. Fig. 4 is a cross-section through the post and its brace on line 4 4, Fig. 3.

In the drawings, *a* is the base composed of the hollow pipe or cylinder, having its lower 40 end crimped or turned inwardly, so as to reduce size of bottom opening, say, one-half of the diameter of the base, so as to retain the earth in the base and yet permit a ready outlet for the water collecting therein.

The post *b*, formed of suitable metal, **U**-shaped in cross-section, extends vertically from the base and a suitable distance into the same. The portion of the post within the base is suitably riveted or otherwise secured 45 therein, and at the upper end of the base the post is provided with offset or with inward

bend *c*, from which the upper portion of the post extends straight and vertically, so that the weight of the post and strain is thrown toward the center of the base, and the post 55 will thereby be straighter and more rigid when properly planted.

d is the brace, at its lower end extending into the base on the opposite side from the post and rigidly fastened to the base. This 60 brace is **U**-shaped in cross-section and of such diameter as to fit within the rear depressed side of the post and extend to the upper end thereof, this brace being longitudinally secured and fitted in the post and leaving the 65 lower portion thereof at a suitable angle to extend across to the opposite side of the base. A most rigid and yet economical and simple construction is thus provided.

The post can be provided with any suitable 70 number of opposite lateral ears *f* from its flat side, perforated as shown, so that rails or fence-panels can be laid thereon and bolted thereto.

The post can be provided with any suitable 75 number of wire-securing buttons or disks *g* on the flat face thereof. Each disk is centrally perforated and formed of metal with a transverse groove *h* across its inner face to one side of the bolt-hole, and corrugated to 80 hold the wire, and clamping-bolt *i* being provided to pass through the button and post, so that in fastening the wire is passed in the groove and the bolt is then tightened and rigidly clamps the button and wire to the post, 85 while the corrugations in the groove rigidly hold the wire against longitudinal slipping.

In planting these posts it is only necessary to bore a hole in the ground of such size that the cylindrical piece will fit snugly therein 90 and thus be held by the rigid compact formation of the groove. The loose earth can be packed into the interior of the hollow base, so that the most firm and rigid base for the post is secured with a minimum amount of 95 digging and packing of earth.

It is evident that various changes might be made in the forms, arrangements, and constructions of the parts described without departing from the spirit and scope of our invention. Hence we do not wish to limit ourselves 100 to the exact construction hereon set forth, but

consider ourselves entitled to all such changes as fall within the spirit and scope of our invention.

Having thus fully described our invention, 5 what we claim as new, and desire to secure by Letters Patent of the United States, is—

1. The fence post comprising the hollow base having its lower end turned or crimped inwardly to partially close its lower end, the 10 post extending into the upper end of the base and secured therein and provided with the inwardly deflected offset at the upper end of the base, the post being approximately U-shaped in cross section and the brace secured 15 to the base and to the post, substantially as described.

2. The hollow base, the post at its lower end

secured in the open end of the base and having the inward offset at the upper open end of the base, the post approximately U-shaped 20 in cross section and the brace secured in the open end of the base, and extending upwardly in the concaved side of the post approximately to the top thereof and approximately U-shaped in cross section and secured to the 25 post, substantially as described.

In testimony that we claim the foregoing as our own we affix our signatures in presence of two witnesses.

AURELIUS E. NEWMAN.
LE ROY JAMES.
